(57) **CLAIM**

The ornamental design for a chromatography column, as shown and described.

DESCRIPTION

FIG. 1 is a perspective view of the chromatography column showing our new design.

FIG. 2 is a right side view of the chromatography column of FIG. 1

FIG. 3 is a front view of the chromatography column of FIG. 1.

FIG. 4 is a left side view of the chromatography column of FIG. 1.

FIG. 5 is a back view of the chromatography column of FIG. 1.

FIG. 6 is a top plan view of the chromatography column of FIG. 1; and,

FIG. 7 is a bottom plan view of the chromatography column of FIG. 1 with the central portion shown in broken lines.

The broken line showing of the inner portion of the bottom of the chromatography column is included for the purpose of illustration and forms no part of the claimed design.
